DESIGN FOR A COMBINED AUTOMOBILE HOOD AND RADIATOR SHELL

John Tjaarda, Birmingham, Mich., assignor to
Briggs Manufacturing Company, Detroit, Mich.,
a corporation of Michigan

Application October 1, 1932, Serial No. 45,192

Term of patent 3½ years

To all whom it may concern:

Be it known that I, JOHN TJAARDA, a subject of the Netherlands, residing at Birmingham, in the county of Oakland, State of Michigan, have invented a new, original, and ornamental Design for a Combined Automobile Hood and Radiator Shell, of which the following is a specification, reference being had therein to the accompanying drawing, forming a part thereof, in which

Fig. 1 is a front view of a combined automo-

bile hood and radiator shell embodying my new design, and

Fig. 2 is a perspective view of the combined automobile hood and radiator shell illustrating the design.

Fig. 3 is a plan view.

I claim:

The ornamental design for a combined automobile hood and radiator shell substantially as shown.

JOHN TJAARDA.
